UNITED STATES PATENT OFFICE.

EDGAR W. BASSICK, OF BRIDGEPORT, CONNECTICUT.

LUBRICATOR.

1,102,127.

Specification of Letters Patent. Patented June 30, 1914.

Application filed June 7, 1913. Serial No. 772,230.

To all whom it may concern:

Be it known that I, EDGAR W. BASSICK, a citizen of the United States, residing in the city of Bridgeport, county of Fairfield, State of Connecticut, have invented certain new and useful Improvements in Lubricators; and I do declare the following to be a full, clear, and exact description of the invention, such as will enable others skilled in the art to which it appertains to make and use the same.

This invention relates to the subject of lubrication, and has specially in view an improvement in lubricators by means of which an absolutely dust-proof lubricator is produced, yet which is so constructed that the supplying of lubricating material to the same is facilitated.

With the above and many other objects in view, the invention contemplates the production of a lubricator of the slideable closure type requiring few parts in its construction, such parts being of a nature that they mutually coöperate to normally preserve the lubricator dust-proof, and include a movable part or closure that can be actuated manually to open the lubricator for supplying lubricating material thereto, the movable part being adapted to automatically return to its closed position to seal the lubricator.

Obviously a lubricator capable of performing the functions generally stated above is necessarily susceptible to changes in details and structural arrangements, a few practical embodiments of which are illustrated in the accompanying drawings, wherein—

Figure 1 is a central vertical sectional view of the improved lubricator. Fig. 2 is a view in elevation of the stem of the lubricator. Fig. 3 is a similar view of the slideable closure. Fig. 4 is a transverse sectional view through the lower portion of the stem. Fig. 5 is a fragmentary vertical sectional view of the closure and partitions. Fig. 6 is a view similar to Fig. 1, but showing a variation of the invention. Fig. 7 is a top plan view of the stem, showing a further variation of the invention.

Referring to the accompanying drawings by numerals, it will be seen that the improved lubricator comprises in its general organization a hollow tubular stem 1, the lower end of which is externally threaded

as indicated at 2, to facilitate the engagement of the stem with a bearing, journal, or the like. The upper end of the stem may be closed by a plug 3, as suggested in Fig. 1, the plug being provided with a notch for the reception of a screw-driver or like tool for adjusting the plug, and also to attach the stem to the part to be lubricated. At intermediate points, the stem 1 is provided with one or more openings 4 which are in alinement, and said openings may, as suggested in Fig. 2, be provided with locking notches 6, for a purpose to be explained.

A closure sleeve 7 slidably surrounds the upper portion of stem 1 and normally seals the openings 4. The sleeve 7, as suggested in Figs. 1 and 3, may have an external ring 8 formed thereon that is milled or otherwise roughened to form a finger-grip that facilitates raising of the sleeve relative to the stem. At, or adjacent, its lower end, sleeve 7 may have an outwardly projecting lug 9 formed thereon to be engaged by the nozzle of an oil can to raise said sleeve. The lower edge of the sleeve is provided with finger extensions, as shown in Fig. 3, which are inverted and form flat supporting ledges 10 that project through the openings 4 and, by engaging the upper and lower edges of said openings, limit the longitudinal movements of said sleeve relative to the stem. The ledges 10 terminate short of the center of the stem 1, as shown in Figs. 1 and 5, leaving a central opening through which the partitions 11 depend. The partitions 11 are longitudinally concaved and have right-angularly projecting flanges 12 at their upper ends that hook over and lie flat on the ledges 10. A spring 13 is seated on the flanges 12 and bears upon plug 3, said spring serving to normally hold the flanges 12 seated upon the ledges 10. The plug 3 obviously holds the spring 13 under tension, and by adjusting the said plug, the tension of said spring may be regulated.

In the form of the invention described, it will be clear that the sleeve 7 can be raised whether by means of the finger-grip 8 or by the lug 9, to uncover the openings 4, and as the partitions are raised with the sleeve, they form independent passages for the lubricant from each opening, thereby preventing communication between the openings such as would permit the lubricant to

pass transversely through the stem. As aforesaid, the sleeve 7 is raised when lubricating material is to be supplied to the stem, and when extensive lubricating is to be performed, it is desirable to hold the sleeve elevated. In such instance, a rotary movement of the sleeve will cause the ledges 10 to enter the notches 5, and thereby hold the sleeve elevated against the pressure of spring 13.

In the form of the invention shown in Fig. 1, two openings 4 are provided in the sleeve 1 and therefore two partitions 11 only are necessary. When more openings are employed, a corresponding number of partitions are employed. For example, in Fig. 4, three partitions are shown, these obviously being used with three openings. In Fig. 1, the partitions are shown as loosely seated on the ledges 10. A variation thereof is suggested in Fig. 5 wherein the partitions are soldered or otherwise permanently fastened to the ledges 10. In this form of the invention, the end flanges are short, and the spring 13 seated on the ledges 10.

A further variation of the invention is suggested in Fig. 6 wherein the sleeve 7 has its top portion provided with inwardly projecting flat ledges 8^a that extend through the openings 4 of stem 1, and the bases of said openings have inwardly projecting ledges 4^a. The free ends of ledges 8^a and 4^a terminate short of the center of stem 1, thereby providing central openings for the passage of lubricating material in addition to the spaces between the ledges. The spring 13 in this form of the invention seats on ledges 4^a and bears against ledges 8^a with sufficient pressure to normally retain sleeve 7 elevated so that the openings 4 are sealed. The upper external surface of the sleeve 7 is provided with a ring 9^a which may be milled or otherwise roughened and forms a grip for the hands of the operator, or a surface that may be engaged by the nozzle of an oil can to depress the sleeve and thereby uncover the openings 4. In this form of the invention the upper end of the stem 1 is closed by the integral cover 3^a which may be notched for the reception of a screw driver and which may also be formed into substantially nut-shape to permit the stem to be grasped by a wrench.

What I claim as my invention is:—

55 1. A lubricator comprising a hollow stem provided with lubricant-admitting openings, a sleeve slidably surrounding the stem and having ledges that project through said openings, partitions depending from the ledges and adapted to prevent communication between said openings, and means for normally retaining the sleeve in position to seal said openings.

60 2. A lubricator comprising a hollow stem provided with lubricant-admitting openings,

a closure for said openings and having portions projecting through said openings into the stem, partitions corresponding in number with the openings and supported by said projecting portions, said partitions forming independent passages leading from the openings into the lower portion of the stem, and means for normally holding the closure in position to seal said openings.

3. A lubricator comprising a tubular stem 75 provided with lubricant-admitting openings, said openings being provided with locking notches, a sleeve slidably and rotatably surrounding the stem and having inturned flat ledges projecting through the openings and adapted to be engaged with the notches to retain the sleeve clear of the openings, and means for normally retaining the sleeve in position to seal the openings.

4. A lubricator comprising a tubular stem 85 provided with lubricant-admitting openings, a sleeve slidably surrounding the stem and provided with flat inwardly projecting ledges that extend through said openings, partitions having flat end flanges that seat 90 upon said ledges, said partitions forming independent passages leading from said openings, a closure for the stem, and a spring seated upon said flanges and bearing upon the closure to normally retain the 95 sleeve in position to seal the openings.

5. A lubricator comprising a tubular stem provided with lubricant-admitting openings, a sleeve slidably surrounding the stem and provided with ledges that project through 100 said openings, partitions carried by the ledges and corresponding in number with, and forming independent passages for conducting lubricating material from, said openings, and means for normally holding 105 the sleeve in position to seal said openings.

6. A lubricator comprising a tubular stem provided with lubricant-admitting openings, a closure sleeve slidable on said stem and having supports extending through the 110 openings, partitions carried by the supports and adapted to form independent passages leading from the openings, and means for normally holding the sleeve in position to seal the openings.

7. A lubricator comprising a tubular stem provided with lubricant-admitting means, a sleeve slidable on the stem and having supports extending into the stem, means carried by the supports for forming independent lubricant-passages within the stem, and means for holding the sleeve in position to normally prevent the admission of lubricating material to the stem.

8. A lubricator comprising a stem provided with lubricant-admitting openings, a closure for said openings slidable on the stem and having supports projecting through the openings, partitions depending from the support and adapted to form inde- 125

pendent passages leading from the openings, and means for normally holding the sleeve in position to seal the openings.

9. A lubricator comprising a tubular stem
5 provided with lubricant admitting openings,
a sleeve slidably surrounding the stem and
provided with inwardly extending ledges
that project through said openings, and a
spring confined between said ledges and a

portion of the stem and acting normally to 10
hold said sleeve in position to close said
openings.

In testimony whereof I affix my signature
in presence of two witnesses.
